WEB BELT LOADER

Michael J. Grebowiec, Kansas City, Kans., assignor to Remington Arms Company, Inc., Bridgeport, Conn., a corporation of Delaware

Application October 4, 1945, Serial No. 620,312

3 Claims. (Cl. 86—48)

1

This invention relates in general to ammunition manufacturing machinery and, particularly, to an improved machine for automatically loading cartridges into a web belt.

In general, cartridges are fed to fully automatic firearms, of the type commonly known as machine guns, by means of cartridge belts. The latter fall into two general classes, the so called link belt which comprises a plurality of metallic links adapted to be held together by an interconnecting cartridge and to separate when the cartridge is removed; and a web belt which comprises two strips of relatively heavy woven material sewed together by transverse rows of stitching to form a plurality of cartridge receiving pockets. In one form of web belt, the width of each pocket is narrower at one end than at the other, the narrower width forming a restriction in the pocket adapted to receive the bullet, the wider portion of the pocket being of sufficient size to accommodate the body of the cartridge. In loading the belt each cartridge is inserted into the wider end of the pocket, bullet end first, and is adapted to be pushed forwardly into the pocket until the shoulder of the case brings up against the restricted portion of the pocket in which position, the bullet is firmly gripped by the pocket restriction and the portion of the case immediately to the rear of the shoulder of the case is gripped by the wider portion of the pocket. For practical purposes, the frictional grip with which the cartridge is held in its pocket must be considerable, and consequently, a very appreciable force is necessary to push a cartridge fully into its pocket.

Heretofore, cartridges have been inserted into the pockets of a web belt by guiding the belt into the bite of a pair of intermittently rotating feed rolls which feed the belt along a horizontal track, each pocket of the belt being momentarily halted opposite a pusher adapted to advance in a direction transverse to the length of the belt to push a cartridge into a pocket thereof, the bite of the feed rolls being relied upon to prevent the belt from moving transversely during the cartridge pocketing operation. The bite of the feed rolls has not been adequate to overcome this tendency and as a result, the cartridges have been improperly arranged and inadequately secured in the successive pockets of the belts.

An object of the present invention is the provision of an improved machine for loading cartridges into the pockets of a web belt. A further object is to provide improved means in a web belt loading machine to prevent transverse move-

2

ment of the belt while loading cartridges therein. A still further object is to provide a web belt holding means arranged to act in conjunction with the bite of the web belt feed rolls to securely hold the belt against transverse movement while inserting a cartridge into a pocket thereof.

These and other objects and advantages of the invention will be described in greater detail in the specification below, having reference to the drawings in which:

Fig. 1 is a schematic fragmentary front elevation of a web belt loading machine having the improved features of this invention.

Fig. 2 is a schematic fragmentary plan view of the machine shown in Fig. 1.

Fig. 3 is a fragmentary elevation of the machine in the direction of arrows 3—3 of Fig. 2.

Fig. 4 is a fragmentary elevation of the machine in the direction of arrows 4—4 of Fig. 2.

Fig. 5 is a schematic fragmentary end elevation in the direction of arrows 5—5 of Fig. 2.

It will be understood that the invention is of general application to machines of the type adapted to insert articles into suitable receptacles and that the particular machine shown in the drawings is by way of illustration only, and does not constitute a limitation of the invention, the scope of the invention being defined by the appended claims.

Referring to the drawings, the machine with which the present invention has application and which, for the purposes of identification, is known to the trade as the Standard Knapp caliber .30 belt loader, comprises in general a base 10 on which is supported a frame 11 having a substantially horizontal bed 12, see Figs. 3 and 4, embodying belt supporting tracks 13 and 14 which constitute extensions of the bed 12. The track 13 is at the leading end of the bed 12 and is provided with a downwardly curved approach surface 13' which is adapted to guide the web belt B up onto the bed 12, the belt being drawn out of a web belt supply box 15 secured to the frame 11 of the machine. The track 14 is secured at the discharge end of the bed, its outer end being supported by a bracket 16.

Cartridges are delivered to the web belt loading machine from a hopper or other suitable source (not shown) by means of an escalator indicated generally at 17 by which cartridges are carried up and over the perimeter of the continuously moving escalator belt (not shown) and fall by gravity down through a vertical guide 18 into a cartridge magazine shown generally at 19 in Fig. 2. The magazine 19 is to the rear of the

longitudinal path of movement of the belt B, as defined by the tracks 13 and 14, see Fig. 2, so that cartridges which are to be delivered from the magazine 19 into the belt must be fed forwardly. Moreover, as delivered from the magazine 19 the longitudinal axes of the cartridges are substantially perpendicular to the belt track.

Referring to Fig. 2, the cartridge feeding mechanism comprises a reciprocable pusher block 20 having a pusher head 22 provided with two cartridge engaging shoulders 23 and 24, the shoulder 24 being adjacent the discharge aperture of the magazine 19 and rearwardly of the shoulder 23. These shoulders 23 and 24 are adapted to progressively engage a cartridge to advance the cartridge in two successive steps into a pocket of the belt in the manner hereinafter described. The pusher block is slidably mounted in suitable guides 25 of the frame 11 substantially perpendicular to the web belt track, the block 20 being reciprocated in its guides 25 by a link 26 which is pivotally connected at one end to the forward end of the block and at its opposite or rear end to a crank pin 27 eccentrically mounted on a rotatable hub 28. The latter is secured on one end of a main drive shaft 29 which is rotatably supported in suitable bushings 30 in a substantially horizontal plane in the frame 11. The opposite end of the shaft 29 is connected to and driven by a power source not shown.

Keyed to the drive shaft 29 is a drum cam comprising a pair of disks 33 held apart in spaced parallel relationship by a cylindrical member 34, each disk having a cam block 35 on its inner face, the blocks being arranged in substantially diametrically opposite relationship.

Pivoted mounted in the frame on a substantially vertical shaft 36 is a rocker or bell crank lever 37, one arm 38 being disposed adjacent the drum cam and having a roller mounted therein arranged to be disposed between the disks 33 of the drum and to be engaged successively by the cam blocks 35 during the rotation thereof to oscillate the rocker in a substantially horizontal plane. The arm 39 of the rocker is associated with an arm holding device indicated generally at 40 for temporarily locking the arm 38 in either of its positions of displacement.

Supported on the rocker shaft 36 beneath the rocker 37 is a second bell crank lever 42, having arms 43 and 44, the arm 43 being provided with a stud 45 which protrudes up through an arcuate slot 46 in the arm 39 of the rocker 37. The arm 44 comprises a relatively thin substantially flat plate having a reinforcing rib 440 on its underside and at its forward edge. The plate 44 constitutes a displaceable bottom for the magazine 19 while the rib 440 constitutes means to move a cartridge, which has been released from the magazine, into the path of the pusher block 22, the face of the rib 440 being arcuate to better embrace the cartridge. Thus, as the rocker 37 is swung counterclockwise (Fig. 2) the engagement of the pin 45 in the arcuate slot 46 of the arm 39 will cause the plate 44 to swing counterclockwise from beneath the column of cartridges in the magazine 19 and enable one cartridge to drop down onto a suitable support (not shown) in front of the rib member 440. Thereafter as the plate 44 is pivoted clockwise, it will be moved beneath the next succeeding cartridge in the magazine to support it while the rib member 440 pushes the released cartridge to a position in front of the shoulder 24 of the pusher head 22. As the rib member 440 returns to its normal position, the pusher head 20 will be advanced to move

the cartridge, bullet end first, toward the web belt, as hereinafter described.

Supported on a substantially vertical post 47, adjacent the edge of the belt track and extending slightly into the path of an advancing cartridge, is a shuttle 48 for partially opening the pockets of the belt to facilitate entry of the cartridges. The shuttle, see Figs. 1 and 5, comprises a disk which is eccentrically mounted on the rotatable post 47 and which rotates in a substantially horizontal plane. A coil spring 47' is carried on the post 47 and is connected to the shuttle to bias it to a normal position. The periphery of the disk or shuttle embodies an eccentric arcuate tongue member 49, the outer edge or periphery of which is grooved. The tongue is substantially wedge-shaped in cross section and is adapted to be engaged substantially tangentially by the bullet of an advancing cartridge and to be rotated thereby against the force of the return spring so as to enter the forward end of the tongue 49 into a substantially closed pocket of the belt. As the wedge-shaped tongue is forced between the upper and lower fabrics of the pocket, the latter will be expanded so as to facilitate entry of the nose of a bullet into the pocket.

As cartridges are advanced by the reciprocating pusher head 22 from the magazine 19 to the web belt B, the latter is fed intermittently along the tracks 13 and 14. The belt feeding means comprises a star wheel 50 located beneath the web belt and carried on one end of a shaft 52 which is rotatably supported in the frame 11 at substantially right angles to the longitudinal axis of the belt track. The star wheel 50 is keyed to the shaft 52 and is disposed in substantially the center of the track with its points or teeth projecting slightly above the plane of the track sufficiently to engage the belt fabric and drag the belt along the track. The rotation of the star wheel 50 is intermittent, being controlled by suitable ratchet mechanism indicated generally at 53, the latter being actuated by a pawl lever 54 which is connected to a yoke 55 pivotally mounted on a rock arm 56 carried on the end of a rock shaft 57. At the opposite end of the latter is a second rock arm 58 having a cam roller 59 in engagement with a drum cam 60 keyed to the main drive shaft 29. The ratchet mechanism is adapted to be adjusted so that the star wheel 50 will advance the web belt in successive steps corresponding to the width of one pocket of the web belt.

Suitable means is provided to hold the web belt 55 down firmly in engagement with the teeth of the star wheel 50 so as to prevent lateral displacement of the belt during the pocket loading operations and comprises a resiliently mounted upper star wheel 62, see Fig. 3, freely rotatable on a stud shaft 63 which is carried on one end of a pivotally mounted arm 64, the shaft 63 being normally in a substantially horizontal plane above the track, at substantially right angles thereto and displaced slightly in advance or to the right (see Fig. 3) of the shaft 52 of the lower star wheel 50. As shown, the bite of the upper and lower star wheels is thus substantially in alignment with the shoulder 23 of the pusher head 22, for the purpose hereinafter described.

The arm 64 has a boss 64' at its opposite end to receive a suitable shaft 65 by which the arm 64 is pivotally mounted on the apertured tongue portion 66 of a hinged bracket 67. The shaft 65 is extended through the tongue 66 to threadedly engage and support a handle 68 on the outside

of the bracket 67. The opposite ends of the bracket have countersinks which provide bearings 69 for the conical ends of suitable pintles 70 which are threadedly secured in bosses 72 located at spaced points on the front of the frame 11. On the end of the hinged bracket 67, opposite the lever arm 64, is a plate 73 welded or otherwise secured to the bracket so as to extend at substantially right angles to its longitudinal axis and adapted normally to lie in a horizontal plane above the web belt. Secured on the underside of the plate 73 by bolts or other fastening means, is a longitudinally slotted guide plate 74 adapted, in its normal position, to overlie the upper surface of the web belt so as to guide the latter along the track. An upwardly extending flange 75 is shown provided along the outside edge of the plate 74, the flange 75 having a longitudinal slot 75' which is adapted to support a microswitch 76 for longitudinal adjustment therein. The microswitch has a projecting contact finger 77 which extends down through the slot 75' of the presser plate 74 and is adapted normally to engage the web belt and to be held thereby in a position to energize the microswitch. If, however, there is no belt passing beneath the presser plate 74, the finger 77 will be freed and drop down to open the microswitch circuit thereby to automatically stop the machine.

At the end of the guide plate 74, opposite that at which the microswitch 76 is secured, is an offset 740 to the underside of which is secured a resiliently supported presser plate or shoe 78, the latter having a belt engaging surface comprising teeth which extend longitudinally substantially in the direction of movement of the belt and which are adapted normally to engage the upper surface thereof to prevent the belt from creeping laterally. Secured on the top of the plate 73 is a bracket latch finger 79 which is arranged to be engaged by a hook 80 on the upper end of a lever arm 82 which is pivotally supported at its lower end in the frame 11 and normally held in latching engagement with the finger 79 by a coil tension spring 83. A suitable crank 84 is provided to actuate the hook 80 for releasing the finger 79. Normally the finger 79 will be engaged by the hook 80 to lock the associated star wheel 62, guide plate 74, and presser shoe 78 of the hinged bracket in operating position.

As pointed out above, the upper star wheel is carried on a pivoted arm 64. The latter is spring biased normally to press the upper star wheel down firmly against the web belt. To this end, a plate 85 is provided having a boss 86 at one end and a longitudinal slot 87 at its opposite end. Suitable apertures are provided in the boss to receive bolts by which the plate 85 may be secured to a flange portion of the pivoted arm 64, the slotted end of the plate extending toward the right end of the machine, as seen in Fig. 1. A counterbored aperture 88 is provided at the slotted end of the plate to accommodate a spring post 89, the lower end of which is arranged to pass freely through the aperture 88 and to be threadedly secured in an aperture of the plate 73 of the hinged bracket 67. The post 89 carries a relatively weak coil spring 90 which seats at its lower end in the counterbore of the aperture 88. The upper end of the spring 90 abuts a collar 92 which is adjustably secured on the upper end of the post. Normally, that is when the hinged bracket is held in position by the latched finger 79, the star wheel 62 will be pressed down against the upper surface of the belt by the force of the coil

spring 90 acting at the extreme right end of the plate 85.

The description thus far has been a general one of features of the web belt loading machine 5 which are in current use.

A feature of the present invention, which enhances the grip of the upper and lower star wheels on the web belt, particularly at the time when the force acting to move the belt transversely 10 is greatest, is shown in Figs. 1 and 3 and comprises a bracket 93 having an aperture 94 at one end and welded or otherwise firmly secured at its opposite end to the plate 73 in a substantially horizontal plane parallel to the plane of the guide plate 74. A second spring post 95 is adapted to be secured at its lower end in the aperture 94 of the bracket 93 and to extend upwardly substantially vertically, when in normal position, through a second counterbored aperture 96 provided in the plate 85, the aperture 96 being immediately adjacent the upper star wheel. A relatively stiff coil spring 97 is carried on the post 95 being supported at its base in the counterbore of the aperture 96. The upper end of the coil 15 spring 97 abuts an adjustable collar or nut 98 on the upper end of the post 95.

In accordance with this construction, the relatively light force provided by the spring 90 and acting to hold the upper star wheel 62 down 20 against the belt is augmented during the second step in the pocketing operation by the force of the relatively stiff spring 97 whereby the bite of the upper and lower star wheels is increased and the tendency for the belt to be displaced or to 25 creep transversely of the track during the pocketing operation is minimized.

The present invention also contemplates an additional feature to positively hold the belt from transverse displacement during the cartridge pocketing operation. Referring to Fig. 3, the frame 11 embodies a bracket 99 to which is secured an upper guide 100 of the pusher block 20. Mounted on the upper guide 100 is an L-shaped bracket 102 (Fig. 5), one leg 103 of which 30 is secured to the top of the guide 100 by suitable fastening means arranged to enable limited lateral adjustment of the bracket with respect to the guide. The leg 104 of the bracket is arranged to overhang the front face of the guide 100 immediately above the pusher head 22 of the reciprocating pusher block 20; and to provide a 35 substantially vertical planar surface 104' which constitutes a way for slidably supporting a vertically reciprocating ram indicated generally at 105. The latter is a substantially rectangular block having longitudinal guide ribs 106 along its opposite sides and is adapted to be held against the vertical way 104' by suitable guide blocks 107 which are secured in spaced parallel 40 relationship on opposite sides of the way 104', each guide block being adapted to make a smooth sliding fit with the respective guide ribs 106 of the ram 105. Longitudinal relief recesses 108 are provided on opposite sides of the ram to receive 45 suitable prong members 109 each of which comprises a relatively thin flat piece of material arranged to be secured in one of the relief recesses of the ram by suitable fastening means and provided at its lower depending end with 50 a pair of sharp tines 109'. The distance between the respective prong members 109 is such that the prongs will straddle a cartridge as it is being advanced by the pusher head 22 into a pocket of the web belt, the tines 109' of the respective 55 prongs penetrating the fabric of the belt at the

adjacent edge thereof and on opposite sides respectively of the pocket.

The ram 105 is arranged to be moved vertically in the guides 107 by drive mechanism comprising a pivoted lever arm 110, the forward end 111 of which is of reduced section and adapted to extend into and to engage the shoulder of a substantially rectangular recess 105' formed in the back of the ram so as to support the ram in the vertical way 104'. The opposite end of the lever arm has trunnions 112 for pivotally mounting the arm in suitable bearing blocks, see Fig. 2, secured to the frame of the machine. Adjacent the forward end of the lever arm is a coil spring 114 which is fastened at its upper end to the underside of the arm 110 and at its lower end to a fixed part of the frame, thus serving to bias the forward end of the lever arm downwardly. The forward end of the lever arm is positively elevated by means of a rotating cam which in the present embodiment, comprises a cam shoe 115 secured on the periphery of the left hand disk 33 of the drum cam 34, see Fig. 2, and adapted to rotatably engage a cam roller 116 supported on a pin projecting laterally from the side of the lever arm 110, the cam roller being located between the lever arm pivot and the coil spring 114. Thus, as the drum cam rotates, the lever arm is positively engaged by the cam and pivoted counterclockwise, as seen in Fig. 5, thereby lifting the ram 105. When the rotating cam shoe disengages the cam roller, the spring 116 will pull the lever arm downwardly thereby releasing the ram 105 so as to enable it to slide down in the guides 107. After being released the ram is not, however, moved down by the lever arm but is driven down forcefully by a compressed spring 117, the latter being arranged to be compressed during the upward movement of the ram. To this end, the lower end of the spring 117 seats in a counterbored aperture in the top of the ram, the upper end of the spring 117 abutting a substantially horizontal foot 118 of a bracket 119 secured to the frame 17 of the escalator. A suitable spring pilot pin 120 is provided which projects downwardly from the foot 118 of the bracket into the coil spring. The upward travel of the ram is adapted to be limited by an adjustable stop which, as shown in Figs. 3 and 5, comprises a bolt 122, the shank of which is slidably secured in an aperture of a bracket 123 secured to the escalator frame 17.

The operation of the machine is as follows: A web belt 5 is brought up onto the track 13 from the belt box 15, and threaded beneath the guide plate 74, presser shoe 78 and into the bite of the upper and lower star wheels 62 and 50, respectively. This operation may be facilitated by gripping the handle 68 and swinging the hinged bracket 67 upwardly and outwardly (see dotted lines Fig. 5), so as to raise the guide plate 74, presser shoe 78, and upper star wheel 62 away from the track. After the belt has been laid in place, the bracket 67 may be swung down and locked in operating position by latching the hook 80 over the finger 79 of the hinged bracket.

As the main drive shaft 29 rotates, the lower star wheel 50 is intermittently rotated drawing the belt forwardly or to the left, as seen in Fig. 1, along the track to successively locate each pocket opposite the pusher head 22. As pointed out above, the latter is provided with two shoulders 23 and 24, respectively, for progressively inserting each cartridge into a pocket of the belt in two successive thrusts of the pusher. In the

operation of the machine, the shoulder 24 is first adapted to engage the head of a cartridge which has been released from the magazine 19 and to advance the cartridge forwardly sufficiently to insert substantially the bullet portion only of the cartridge into a pocket of the belt. This may be termed the first step of the pocketing operation and is facilitated by the eccentrically mounted shuttle 48, the tongue 49 of which is adapted to be tangentially engaged by the nose of the advancing bullet and pushed thereby between the upper and lower fabrics to open the pocket and guide the bullet therein. The pusher is then retracted and the belt advanced along the track by the lower star wheel 50 a distance corresponding to the width of one pocket. The pusher is then adapted to be advanced forwardly again this time to engage its shoulder 23 against the head of the partially pocketed cartridge and force the latter to its final position in the pocket. This operation may be termed the second pocketing operation. It will be clear that as the partially pocketed cartridge is moved from the first pocketing operation into position for the second pocketing operation, it will pass into the bite of the upper and lower star wheels 62 and 50 respectively causing the upper wheel 62 to be displaced upwardly slightly against the restraining force of the relatively light spring 90. With the partially pocketed cartridge in this position, the web belt is momentarily halted and the prongs 109 of the ram 105 thereupon descend on the opposite sides of the partially pocketed cartridge and penetrate the edge of the belt so as to positively hold the belt and prevent any transversed movement thereof relative to its direction of travel. The pusher 20 then makes its second pocketing stroke during which its shoulder 23 engages the head of the partially pocketed cartridge and moves it forwardly into final position in the pocket. It will be evident that as the relatively large shoulder and body portions of the cartridge are pushed into the pocket, the force tending to move the belt transversely increases; and that the upper star wheel will be displaced upwardly by the increased size of the body and shoulder portions of the cartridge. However, any tendency of the belt to move transversely is positively prevented by the prongs of the ram and the additional displacement of the upper star wheel is resisted both by the relatively weak spring 90 and by the relatively stiff spring 97 acting in conjunction therewith so that the grip or bite of the upper and lower wheels is increased, thereby further minimizing any tendency of the belt to creep or move transversely during the second pocketing operation. It will be appreciated that during the second pocketing operation, the shoulder 24 of the pusher will have partially advanced a second cartridge 45 into the next succeeding pocket of the belt as described above. As the pusher again recedes, the vertically reciprocating ram 105 is elevated by the cam actuated lever arm 110 thereby withdrawing the tines 109' of the prongs 109 from the web belt. The belt is then advanced along the track for the next succeeding pocketing operation. Throughout the pocketing operations, the contact finger 77 of the microswitch 76 will slide over the web belt, but as soon as the belt runs out the finger 77 will drop down thereby operating a microswitch to shut off the machine.

What is claimed is:

1. In a machine for inserting cartridges into a web belt provided with individual cartridge receiving pockets disposed transversely of said belt:

the combination comprising a belt receiving table and support therefor; cartridge inserting means comprising a reciprocating pusher adapted to thrust cartridges endwise over an edge of said belt and into said pockets; means for holding said belt against transverse displacement under the thrust of said pusher comprising a pair of holding feet adapted to engage said belt adjacent said edge thereof and on opposite sides of the cartridge being inserted therein and means for reciprocating said feet toward and away from said belt in timed relation to the movement of said pusher; and belt feeding means comprising a lower notched wheel adapted to partially encircle a cartridge in a pocket in said belt, an upper notched wheel cooperating with said lower notched wheel and rotatably supported in a pivoted arm, and a plurality of spring means associated with said arm and urging said upper notched wheel toward said lower notched wheel.

2. Apparatus according to claim 1 in which a part only of said plurality of springs are effective during the insertion in a belt pocket of the bullet

and neck portion of a cartridge, and the entire plurality are effective during the insertion of the shoulder and body portions of a cartridge.

3. Apparatus according to claim 1 in which the pivot support of said pivoted arm is an element of an assembly which is rotatable about a fixed support from an operating position to a position affording access to said table, lower notched wheel and associated parts.
